[57] CLAIM

The ornamental design for a jewelry rope chain, as shown and herein described.

DESCRIPTION

FIG. 1 is a front elevational view of a first embodiment of our new design lined to show the color gold;

FIG. 2 is a right side elevational view taken in the direction of line 2—2 in FIG. 1, showing a portion of the new design lined to show the color gold and another portion lined to show the color silver;

FIG. 3 is a rear elevation view of the first embodiment lined to show the color silver;

FIG. 4 is a front elevational view of a second embodiment of my new jewelry rope chain showing a heloiodical strand of the rope chain lined to show the color gold and the other heloiodical strand of the rope chain lined to show the color silver, of which the opposite view is a mirror image; and, FIG. 5 is a front elevational view of a third embodiment of my new jewelry rope chain wherein a channel of the heloiodical rope chain is of one color and the other channel of the rope chain is a second color, of which the opposite view is a mirror image.
